Patented Mar. 27, 1973

226,546

END FRAME UNIT FOR A TABLE AND BENCH COMBINATION

Marvin J. Priefert and William D. Priefert, both of
R.R. 1, Mount Pleasant, Tex. 75455

Filed July 12, 1971, Ser. No. 161,408

Term of patent 14 years

Int. Cl. D6—02

U.S. Cl. D6—192

FIG. 1 is a perspective view of an end frame unit for a table and bench combination showing our new design;

FIG. 2 is an end elevational view;

FIG. 3 is a side elevational view looking in the direction of the line 3-3 in FIG. 2;

FIG. 4 is a side elevational view looking in the direction of the line 4-4 in FIG. 2; and

FIG. 5 is a top plan view.

We claim:

The ornamental design for an end frame unit for a table and bench combination, substantially as shown.
